TOE-DANCING SLIPPER

Elia Di Rienzo, Brooklyn, N. Y.

Application June 8, 1931. Serial No. 542,776

4 Claims. (Cl. 36—8.3)

This invention relates to a method and means for manufacturing dancing slippers, particularly slippers for use in toe-dancing, and contemplates the provision of a blank which can be easily and quickly transformed into a slipper without the usual expenditure of time and labor involved in the manufacture of said slippers.

Hitherto it has been the custom in making dancing slippers to make the upper of the slipper in three pieces. One of these pieces constituted a toe piece and when laid out flat was substantially bell-shaped. In making a shoe, the sole is placed on the last with its bottom in contact with the last, leaving its upper portion exposed. The 15 unfinished and unformed upper is then drawn over the last inside out and attached to the sole by cementing, riveting or sewing with a McKay or Goodyear turn sole sewing machine. In attaching the upper to the sole it was always necessary to form several pleats in the upper in order to produce the proper shape. This pleating of the upper during the attaching operation presented great difficulties since it was only with the exercise of extreme care that the operator could get the pleats in the proper place and arrange them so as to avoid extremely large protuberances. Moreover, it was impossible to attach the pleats to the sole securely enough to make the shoe durable. This was evidenced by the fact that the 25 shoes always gave out first at the pleats which drew away from the sole.

It is an object of this invention to provide an upper for such a shoe which is a symmetrical blank having a folding line through its middle and each 30 side of which has a shape closely resembling the shape of the well known sabot or wooden shoe. The entire blank could be described as having the shape of a V, the apex of which is bow shaped.

The invention resides in the novel combinations hereinafter described and claimed, reference being made to the accompanying drawing in which:

Fig. 1 represents an inverted plan view of a slipper embodying this invention.

Fig. 2 is a vertical longitudinal section of the same.

Fig. 3 is a detailed vertical section showing the method of manufacturing the slipper.

Fig. 4 is a section of the upper showing the central seam.

Fig. 5 shows the upper.

In the drawing numeral 5 designates the outer sole and 6 is the upper which is preferably sewed at 7 to the outer sole but could be cemented or riveted. The upper is preferably made in one piece,

folded along the line 19 and seamed at the back 8 where the end of the shanks 9 are joined together. The toe portion 10 of the upper is formed by sewing the edges of the bow 11 together from the sole to the folding line 19. Forming the toe 60 in the foregoing way provides a reinforcement to the central part and it insures a uniform stretch of material about the forward part of the slipper, as indicated in Figs. 1 and 2.

A toe stiffener 12 is cemented to the inner part 65 of the upper and constitutes a rigid back for the toe although sometimes the toe stiffener is omitted when it is preferred to have a soft toe. A lining 13 covers the inner part of the upper and it has an opening 14 for the insertion of 70 a foot. The lining is substantially the same configuration as the upper and its lower portion is sewed to the sole therewith. This bow is so proportioned with respect to the rest of the blank that when the blank is folded along its folding line and the edges of the bow are sewn together and the ends of the legs of the V are sewn together the upper of the shoe is completed in its proper form and shape. Consequently, when a shoe is assembled on the last the necessity for 75 pleating the upper during the attaching operation is entirely eliminated. This fact reduces the time necessary for this operation to about one-fifth of the time hitherto consumed and entirely excludes the painstaking part of the operation. 80 Moreover, the shoe produced in this manner is entirely free from any ridges on the dancing surface. This is very important since the presence of such ridges is very apt to unbalance the dancer and make the shoes very uncomfortable to the 85 wearer.

The provision of such a blank makes possible the manufacture of dancing shoes the uppers of which are free from wrinkles and unnecessary seams and are neat in appearance. Moreover, 90 a great deal of the sewing that was necessary in the uppers hitherto used is eliminated.

I also contemplate making the blank in two pieces, in which event the sides of the blank will be separated along the folding line and when 100 assembled will be sewn along the folding line. A very distinct advantage of the use of these blanks in the manufacture of shoes is that the shoes can be made by machinery as well as by hand. The shoes hitherto known which required 105 pleating at the toe could only be made by hand. This presented a serious drawback to their manufacture on a large scale. This drawback is entirely eliminated by my invention.

The method of manufacturing a slipper in ac- 110

cordance with my invention will be described with reference to Figs. 3 and 5. The blank shown in Fig. 5 is first folded along the line 19 and the edges of the bow 11 are sewn together. Then the 5 ends of the legs 9 of the V are sewn together. The result of this operation is the upper in its final form. A sole is next attached to a last with its inner side up. The upper is turned inside out and drawn over the last so that its bottom edges 10 9' overlap the edges of the sole. These bottom edges of the upper are then secured to the inside of the sole by cementing, riveting or sewing with a McKay or Goodyear turn sole sewing machine. The shoe is then removed from the last and 15 turned right side out.

An inner sole 17 can be cemented or fastened by means of nails 18 to the outer sole. In manufacturing the slipper while on the last it is turned inside out and it is preferred that the inner sole 20 be cemented on the inside of the outer sole after the slipper is taken from the last and turned. Modifications of the invention may be made. For example the upper can be made in two sections and seamed along the dotted lines 19, thus 25 having the circular seam continuous to the opening 14 at the top.

I claim:

1. A method of manufacturing dancing shoes which comprises forming a blank in the shape 30 of a V with a bow-shaped vertex, folding the blank along its center line so that the sides of the bow coincide and the ends of the legs of the V coincide, sewing the ends of the legs of the

V together and the sides of the bow together, thereby forming a complete upper, placing a sole on the last with its inner side up, turning the upper inside out and drawing it over the last until its bottom edges overlap the edges of said sole and attaching the bottom edges of said upper to the edges of said sole.

2. A toe dancing slipper comprising an outsole terminating a substantial distance short of the toe of the slipper, and an upper attached to said outsole without the conventional folds or plaits at the toe portion thereof, said upper having a seam extending from the front end of said outsole along the longitudinal axis of said upper at least to the top of the toe of said shoe.

3. A toe dancing slipper comprising an outsole terminating a substantial distance short of the toe of the slipper, and an upper attached to said outsole without the conventional folds or plaits at the toe portion thereof, said upper having a seam extending along the longitudinal axis thereof from the front end of the outsole to the front end of the foot receiving opening of said upper.

4. A toe dancing slipper comprising an outsole terminating a substantial distance short of the toe of the slipper, and an upper attached to said outsole without the conventional folds or plaits at the toe portion thereof, said upper having a seam extending along the longitudinal axis thereof from the front end of said outsole to a point adjacent the top of the toe of said upper.
